United States Patent Office

Des. 232,897
Patented Sept. 24, 1974

232,897

ELECTRIC PERCOLATOR

Ronald B. Kemnitzer, Lisle, Ill., assignor to Sunbeam
Corporation, Chicago, Ill.

Filed Jan. 29, 1973, Ser. No. 327,364

Term of patent 14 years

Int. Cl. D7—04

U.S. Cl. D7—62

Fig.4.

Fig.5.

Fig.6.

FIG. 1 is a perspective view of an electric percolator showing my new design;

FIG. 2 is a top plan view thereof;

FIG. 3 is a side elevational view thereof;

FIG. 4 is a rear elevational view thereof;

FIG. 5 is a front elevational view thereof; and

FIG. 6 is a bottom plan view thereof.

I claim:

The ornamental design for an electric percolator, as shown.
